EGG CARTON AND FILLER

Edward J. Lawless, Chicago, Ill.

Application April 23, 1937, Serial No. 138,510

3 Claims. (Cl. 217—32)

This invention relates to improvements in packaging devices, and more particularly to an improved carton and filler for containing and supporting eggs for storage and transportation.

It has become the practice to make up packages of twelve eggs in cartons as eggs are usually purchased by the dozen, and to divide the cartons into pockets to receive the individual eggs by placing fillers forming transverse and longitudinal partitions in the cartons to form the pockets.

It is an object of this invention to provide an egg carton that may be readily stamped from a sheet or roll of heavy paper or cardboard and easily assembled to receive a pocket-forming filler. It is another object of this invention to form the tops and bottoms of the cartons with means coacting with the transverse partitions of the filler to secure the tops and bottoms of the containers in closed position, and in addition thereto provide the tops with releasable locking means adapted to engage the transverse partitions. It is a further object of this invention to provide the filler with separated rows of egg-receiving pockets and provide each pocket with egg-supporting means preventing the eggs from engaging the sides or bottom of the containing carton. It is a still further object of this invention to provide the carton with means to observe the color or character of the contained eggs without opening the carton.

With these and other objects in view reference is made to the attached sheet of drawing illustrating a preferred form of this invention, with the understanding that minor changes may be made without departing from the scope thereof.

In the drawing:—

Figure 1 is a top plan view of this improved egg carton with the top opened and showing the eggs as received in the pockets formed by this improved filler.

Figure 2 is a view in transverse vertical section taken on the line 2—2, Figure 1, showing the tops and bottoms of the carton in the engaged closed position.

Figure 3 is a fragmentary view in longitudinal vertical section taken on the line 3—3, Figure 1, with parts broken away.

Figure 4 is a detail view in elevation of a longitudinal supporting strip.

Figure 5 is a detail view of a transverse partition card.

The embodiment of this invention as illustrated includes a carton particularly designed for containing and transporting eggs with a filler

to be contained therein to support the eggs in spaced-apart relation in the carton.

The carton and filler parts are preferably stamped or otherwise cut from flexible fibrous material, such as heavy paper or cardboard. While the carton may be of any shape desired, the one illustrated is a commercial type designed to contain two rows of six eggs each.

In the carton illustrated in Figures 1, 2 and 3 the rectangular ends 1 are joined by elongated rectangular sides 2, the longitudinal edges of which are extended to form top and bottom closures 3 and 4, each of which are formed to meet along the longitudinal center line of the carton with flaps 5 and 6 bent to extend inwardly in contact with each other, as shown in Figure 2, and secured as hereinafter described.

The filler includes a plurality of transverse rectangular cards or partitions 7 dividing the carton into six equal sections supporting two pairs of longitudinal rectangular egg-supporting strips 8, with each strip in each pair equally spaced apart from the other with the pairs equally spaced apart throughout their length by engagement with the partition cards 7 to form therewith twelve egg receiving and supporting pockets, as shown in Figure 1. The supporting strips 8 are preferably a little more than half the height of the partition cards 7 and the strips 8 and partition cards 7 are interconnected with each other to form a filler unit independent of the carton which may be readily assembled therewith or removed therefrom.

The strips 8 and cards 7 are interconnected so that the strips of each longitudinal pair are nearer each other at the bottom than at the top, thereby providing egg-receiving pockets which taper toward the bottom to support the eggs and prevent the lower ends of the eggs coming in contact with the bottom of the carton. The partition cards 7 are spaced apart from each other and from the ends of the carton at a distance usually employed in egg cartons and the upper longitudinal edges of the strips 8 are likewise spaced apart. The filler being constructed of flexible material with the longitudinal sides of the pockets arranged at an angle to the bottom of the carton forms egg-receiving pockets which engage and support each egg above the bottom of the carton so that jars or blows received by the carton during handling or in transportation will only wedge the eggs into the pockets without injuring the eggs.

This result is obtained by providing four slits in the bottom of each partition card 7, as shown

in Figure 5, through which the strips 8 pass. Each slit has a portion 9 perpendicular to the bottom of the card 7 and an oppositely-disposed portion 10 extending at approximately 15° 5 from the perpendicular from the bottom of the card 7. The top of each slit ends in a substantially square portion 11 with one side forming a slightly offset extension of the perpendicular portion 9 and the body of the card between the bottom of the square portion 11 and the top 10 of the angular portion 10 projecting toward the perpendicular portion 9 under the offset portion of the top portion 11 to form a locking lug 12. The bottom of each slit is expanded with the part 15 13 below the perpendicular portion 9 cut away at an angle parallel to the angular portion 10. These slits are arranged in complementary pairs with the respective square portion spaced apart from the vertical center line of the card 7 and 20 the vertical edges thereof. Each longitudinal strip 8 is provided with a plurality of equally spaced apart notches 14 along its top horizontal edge and the body below each notch is provided with a rectangular vertical slot 15 so arranged 25 that when the strips 8 are inserted in the slits of the cards 7, the bottoms of the notches 14 will engage the tops 11 of the slits and the locking lugs 12 of the cards will engage in the slots 15, as shown in Figure 5, so that the strips 8 will 30 be interconnected with the partition cards 7 at an angle to the vertical to form pockets tapering toward the bottom.

The outer side portions of the square portions 11 of each pair of slits in the partition 35 cards form vertical continuations of the angular portions 10 of the slits beyond the lugs 12, so as to cause the strips to bulge outwardly between the top and bottom edges thereof when they are forced into engagement with said angular side 40 portions upon insertion of the eggs in the pockets. Thus, the eggs will be more firmly held in the pockets by the side walls of the pockets embracing a portion of the sides of the eggs so that 45 the eggs are effectively prevented from being dislodged from the pockets in the event the carton is inverted.

The locking lugs 12 of the slits are tapered so as to be freely received in the slots 15 of the strips when assembled with the partition cards. 50 When the strips are caused to bulge outwardly by the insertion of the eggs in the pockets, the lugs will be forced into the slots 15 and form a wedging connection between the strips and the partition cards to firmly hold the strips in assembled position with the partition cards.

It is preferable to provide the flaps 5 and 6 of the top and bottom portions 3 and 4 of the carton with equally spaced-apart slits 16 to receive the edges of the partition cards 7 when the 60 flaps are bent inward in closing the top and bottom of the carton. It is preferable to provide a releasable locking means for the top 3 of the carton to allow the opening and closing for the removal of eggs. In the form shown the outer 65 edges of each slit 17 in the flaps 5 of the tops 3 of the carton is cut out to form a notch 17 and the bottom expanded into a rectangular portion 18 forming complementary locking lugs 19 below each notch 17. Each partition card 7 70 is provided with a central circular perforation

20 with its upper edge sufficiently spaced apart for the top of the card 7 to allow the locking lugs 19 to engage therein when the carton is closed and hold the flaps 5 in releasable engagement with the cards 7. 5

It is also preferable to provide each side 2 of the carton with circular openings 21 opposite each pocket formed by the filler and adjacent the top of the carton through which the color of the eggs in the carton may be observed without opening the top of the carton. 10

It is to be understood that while this improved carton and filler when combined provide an improved container for eggs, the carton may be used with other fillers, provided the transverse partition cards are perforated to be engaged by the locking lugs on the top flaps, without departing from this invention, and, likewise, the improved filler may be employed with other cartons, may be constructed to provide a greater or lesser number of egg pockets, or may be stacked one upon another in cartons or boxes of greater depth by providing horizontal partitions of any desired character between the filler units. 15

What I claim is:

1. A filler for egg cartons or the like, including a plurality of transverse partitions, each partition being provided with a pair of slits extending upwardly from its lower edge to approximately the longitudinal center line of the partition, the lower portion of each slit being of substantially inverted V-shape, the outer edges of each pair of slits immediately above said portions diverging upwardly and the corresponding inner edge portions of each pair of slits being substantially vertical, the slits immediately above the last-mentioned portions being shaped to form tongues which project toward one another, and the slits forming slots immediately above said tongues, and flexible longitudinal strips interlocked with said partitions and having equally spaced apart notches upon their upper edges and apertures aligned with such notches and arranged immediately below the same, the tongues of the partitions extending through said apertures, and the body portions of the strips engaging the diverging edges of the partitions so as to support the strips in upwardly diverging relation, each strip being of unbroken formation between its notches and apertures so as to provide an unbroken wall immediately above the tongues of the partitions. 35 40 45 50

2. The structure of claim 1, wherein an edge of each slot contiguous to and immediately above each tongue is arranged at an angle to the same edge immediately below said tongue to impart a bend extending longitudinally of each strip when wedged upon the tongues. 55

3. A filler as claimed in claim 1, wherein the upper edge of each tongue is arranged parallel to the lower edge of the partition of which it is a part, and the lower edge of each tongue tapers downwardly toward the lower edge of the partition whereby the tongues force the portions of the strips between the notches and apertures into engagement with edges of the partitions above the tongues when the strips are wedged thereon. 60 65 70
